UNITED STATES PATENT OFFICE

ERNEST O. FREDERICKS, OF NEW YORK, N. Y., ASSIGNOR TO E. FREDERICKS, INC., OF NEW YORK, N. Y., A CORPORATION OF NEW YORK

HAIR CURLING DEVICE

Application filed October 12, 1928. Serial No. 311,994.

This invention relates to hair curling devices, and particularly to devices for winding tresses of hair for hair-waving treatments.

5 In general, it is an object of the invention to provide a device of the character described which is simple and economical of manufacture and on which tresses of hair may be readily and securely wound.

10 A more specific object of the invention is directed to the provision of improved means to prevent slipping of the hair during a winding operation.

Another object is to provide improved means for facilitating the winding of hair on a curling device.

Other objects of the invention will in part be obvious and will in part appear hereinafter.

20 The invention accordingly comprises an article of manufacture possessing the features, properties and the relation of elements which will be exemplified in the article hereinafter described, and the scope of the application of which will be indicated in the claims.

For a fuller understanding of the nature and objects of the invention reference should be had to the following detailed description 30 taken in connection with the accompanying drawings, in which:

Figure 1 is a partly sectional view of one form of hair-curling device constructed in accordance with the invention;

35 Fig. 2 shows this form of curling device with the hair wound thereon;

Fig. 3 is a partly sectional view of another form of curling device constructed in accordance with the invention; and

40 Fig. 4 is a fragmentary view of a modified form of curling element.

In winding tresses of hair on a curling device, and particularly in the "Croquignole" method of winding, in which laterally spread tresses of hair are wound upon themselves on a curling device which is ordinarily of somewhat greater extent at its ends than at an intervening portion against which the outer ends of the hair are held, considerable difficulty has been experienced because of the

tendency of the hair to slip or bunch during the winding operation. This is true particularly in the "Croquignole" method of winding, since the hair is wound upon itself, and the outer ends of the hair must be automatically and securely held in place so that they will not slip at any time while the inner portions of the hair are being wound thereover; and in this method of winding it is also particularly desirable that no rotation of the curling element in a direction contrary to the winding direction can be caused by the operator. It will thus be seen that it is desirable to provide simple and effective means to prevent such slippage of the hair during the winding operation as would prevent the same from being readily wound, or would cause the same to bunch; and it is also desirable to provide means for permitting a free rotation of the curling device in the direction in which the hair is to be wound, while resisting rotation in the opposite direction.

The present invention contemplates the provision of means on a curling element 75 which will catch and hold the hair in a manner which will reduce to a minimum the danger of slipping. It also contemplates the provision of improved means for resisting rotation of the curling element in the direction opposite to that in which the hair is wound, and particularly, the provision of rotation-resisting means of a simple and economical type and of a nature such that it will occupy no unnecessary space, and will eliminate the danger of hair catching therein. In order to accomplish these purposes, there is provided in the exemplification shown in Fig. 1 a curling element 5 having end portions 6 and 7 the diameter of which is relatively large, and an intermediate portion 8 the diameter of which is relatively small so as to accommodate the greater number of layers formed in winding the longer tresses of the hair by the Croquignole method. In 95 order to bind the outer ends of the tresses of hair securely at this intermediate portion to prevent slipping, the portion 8 is formed with a series of annular grooves 9. Preferably, it is also formed with means such as the 100

longitudinal grooves 10 intersecting the annular grooves and providing shoulders along the edges of the annular grooves and providing transverse indentations, to cooperate with the annular grooves to prevent slipping. The annular grooves are preferably deep enough to permit several strands of hair to be received thereby; and when longitudinal grooves are provided the depth of these 10 grooves is preferably commensurate with the depth of the annular grooves. Any desired form of clip may be utilized in connection with such a device to assist in holding the hair in place, if desired.

15 The curling device is provided at one of its ends with a knob 11 by which the same may be rotated, and at the opposite end with an attaching element 12 which is adapted to be held permanently in place when the device is in use. The attaching element 12 has formed thereon a sleeve 13 which fits into a recess 14 in the end of the curling element 5. The sleeve is provided with an annular groove 15 into which a pin 16 extends from 20 the curling element to prevent the sleeve from sliding out of the recess 14. In order to prevent the relative rotation of the sleeve 13 and the curling element 5, there is provided a spring 17, which fits within the sleeve and within a reduced diameter recess 18 extending inwardly from the recess 14. This permits the knob to be turned readily to rotate the curler in one direction, when the attaching element 12 is secured in place, while effectively preventing an accidental contrary movement of the knob which would interfere with the proper winding of the hair.

25 In the form exemplified in Fig. 3, the attaching element 12 is secured in place by a rod 19 extending through, and rotatably mounted within, the curling element and having at its free end a disc 20 which fits within a recess 21 in the knob. In this exemplification the attaching element is exemplified as 30 provided with a sleeve 13' in which no groove is provided. In Fig. 4 there is shown a curling element formed only with annular grooves 9.

35 It will thus be seen that not only is an exceedingly simple and economical arrangement provided, but that the easy winding of hair in a correct and efficient manner is assured; and the practical availability of the Croquignole method of winding hair is greatly increased.

40 Since certain changes may be made in the above article, and different embodiments of the invention could be made, without departing from the scope thereof, it is intended that all matter contained in the above description or shown in the accompanying drawing shall be interpreted as illustrative and not in a limiting sense.

45 It is also to be understood that the following claims are intended to cover all of the

generic and specific features of the invention herein described and all statements of the scope of the invention which as a matter of language might be said to fall there between.

Having described my invention, what I claim as new and desire to secure by Letters Patent is:

1. A hair curling device, comprising a curling element and an attaching element, said curling element being formed intermediate its ends with a series of annular grooves and with longitudinal grooves intersecting said annular grooves, means for rotatably connecting said attaching and curling elements, and means to prevent relative rotation of said elements in one direction while permitting relative rotation thereof in the other direction. 75

2. A hair curling device, comprising a curling element formed intermediate its ends with a series of annular grooves, and means providing shoulders along said grooves whereby tresses of hair will be securely bound to the curling element against slipping when the element is rotated. 85

3. A hair curling device, comprising a curling element the diameter of which is reduced from its ends to an intermediate portion, said intermediate portion being formed with a series of annular grooves and with one or more longitudinal grooves intersecting said annular grooves whereby tresses of hair will be securely bound to the curling element against slipping when the element is rotated. 95

4. A hair curling device comprising a curling element the diameter of which is reduced from its ends to an intermediate portion, said intermediate portion being formed with a series of annular grooves of sufficient depth to receive a plurality of strands of hair for securing tresses of hair against slipping when the element is rotated to wind the tresses of hair upon themselves. 100

5. A hair curling device, comprising a curling element formed intermediate its ends with a series of annular grooves of sufficient depth to receive a plurality of strands of hair whereby tresses of hair will be securely bound to the curling element against slipping when the element is rotated. 110

6. A hair curling device, comprising a curling element formed intermediate its ends with a plurality of longitudinal grooves and with other grooves intersecting said longitudinal grooves, for securing tresses of hair against slipping when the element is rotated. 115

7. A hair curling device, comprising a curling element and an attaching element arranged for relative rotation, and means contained within one end of the curling element for preventing relative rotation of said elements in one direction while permitting relative rotation thereof in the other direction, said means including a member extending from said attaching element and within said end of the curling element. 125 130

8. A hair curling device, comprising a curling element having a smaller diameter at its center than at its ends, an attaching element at one end of the curler, a knob at the other end of the curler, and means for securing said attaching element to the curling element so as to permit relative rotation thereof in one direction and to prevent relative rotation thereof in the other direction, the last-mentioned means being contained within one end of the curling element.

9. A hair curling device, comprising a curling element, an attaching element disposed against one end of the curling element, the aforesaid end of said curling element being formed with a recess having a reduced diameter portion, a sleeve secured to the attaching element and extending into said recess, a coil spring fitting within said sleeve and extending into the reduced diameter portion of said recess and serving to prevent relative rotation of the curling element and the attaching element in one direction.

10. A hair curling device, comprising a curling element, an attaching element, means for connecting said elements to prevent relative axial movement thereof, and means at the end of the curling element adjacent the attaching element to prevent relative rotation of said elements in one direction, the latter means comprising aligned interior bearing surfaces on the curling element and the attaching element, respectively, and a helical spring adapted to be expanded against said bearing surfaces.

11. A hair curling device, comprising a curling element, an attaching element disposed against one end of the curling element, pin and groove means adjacent said end for rotatably securing said elements together, and further means adjacent said end and comprising a helical spring for preventing relative rotation of said elements in one direction.

12. A hair curling device, comprising a curling element formed intermediate its ends with grooves extending in the direction in which the hair is wound, said grooves being of sufficient depth to receive a plurality of strands of hair one upon the other and of sufficient width to receive a plurality of strands of hair alongside each other, whereby the ends of tresses of hair may be pressed into the grooves and held therein at the beginning of the winding, and whereby the winding of the tresses of the hair will cause the strands thereof to be pressed more firmly into the grooves to hold the hair firmly in place on the curler.

60 In testimony whereof I affix my signature.
ERNEST O. FREDERICS.
